UNITED STATES PATENT OFFICE.

GUSTAF F. JOHNSON, OF SUPERIOR, WISCONSIN, ASSIGNOR OF ONE-HALF
TO WILLIAM GEORGE ROBERTS, OF SUPERIOR, WISCONSIN.

ENVELOP-SEALER AND STAMP AND LABEL AFFIXER.

No. 831,076.

Specification of Letters Patent.

Patented Sept. 18, 1906.

Application filed January 4, 1906. Serial No. 294,585.

To all whom it may concern:

Be it known that I, GUSTAF F. JOHNSON, a citizen of the United States, residing at Superior, in the county of Douglas and State of Wisconsin, have invented a new and useful Envelop-Sealer and Stamp and Label Affixer, of which the following is a specification.

The invention relates to improvements in devices for sealing envelopes and affixing stamps and labels to letters, packages, and various articles.

The object of the present invention is to provide a simple, inexpensive, and efficient device adapted to moisten and seal envelopes and capable of affixing stamps to the same and of applying gummed labels to various articles.

A further object of the invention is to provide a device of this character designed particularly for use on a desk and adapted when not in use to have its moistening means supported out of contact with the desk.

A further object of the invention is to provide an envelop-sealer and stamp and label affixer having package-opening means adapted also to support the moistening-roller in a slightly-elevated position out of contact with the supporting-surface upon which the device is placed.

Another object of the invention is to provide a device having a conveniently-arranged blade adapted for opening envelopes and capable of use for various other purposes.

It is also the object of the invention to afford convenient access to the stamps or labels and efficient means for feeding the same from the device.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a perspective view of an envelop-sealer and stamp and label affixer constructed in accordance with this invention. Fig. 2 is a longitudinal sectional view of the same. Fig. 3 is a reverse plan view. Fig. 4 is a transverse-sectional view on the line 4-4, Fig. 3. Fig. 5 is a detail

perspective view of the holder or receptacle for the stamps or labels.

Like numerals of reference designate corresponding parts in all the figures of the drawings.

1 designates the body of the device, consisting of an oblong casing and comprising a sheet-metal plate and integral sides 2, which are resilient and which are extended at the ends of the casing to provide opposite bearing-arms 3 and 4, and the latter are arranged in pairs, and each have journaled between them rollers 5 and 6. The arms 3 and 4 are provided with suitable perforations or bearing-openings for the reception of the journals 7 and 8 of the rollers 5 and 6, and these journals may be of any desired construction. The roller 5, which is designed for applying moisture to an envelop for sealing the same and also for affixing stamps and labels, is constructed of absorbent material, such as felt, and it is provided with a central core 9, of wood or other suitable material, on which the felt is arranged. The sheet metal of which the body or casing is constructed is split longitudinally to form the arms 3, and the intermediate portions of the material lying between said bearing-arms 3 is bent outward and cut to form a pair of tapering 85 projecting portions 10, which extend over the felt roller when the device is arranged as illustrated in Fig. 1 of the drawings. When the moistening-roller is not in use, the device is inverted and the tapering projections 10 90 form supporting-feet to hold the moistening-roller in a slightly-elevated position out of contact with the desk or other supporting-surface upon which the device is placed. This enables the device to be used on a desk 95 without liability of injuring the finish of the same or soiling the papers or other articles lying upon the top of the desk. The tapering projections or feet are also adapted to be used for opening small packages, and they 100 are spaced from the moistening-roller, as clearly shown in Fig. 2, so that when they are used for this purpose the moistening-roller will not come in contact with the package being opened. The side edges of the 105 tapering projections are sufficiently sharp to enable them to readily sever a string or cut the paper of a package. The felt roller may be moistened by dipping it into a receptacle containing a quantity of water or by any 110 other suitable means, and it is applied by running the roller over a surface, as will be

115

readily understood. The casing is of a size to enable it to be readily held in the hand, so that the device can be conveniently grasped and used.

5 The roller 6, which is rubber-covered, is adapted to apply the necessary pressure for sealing envelopes or other articles, and it is preferably provided with a wooden body portion, but may be constructed in any desired manner. The moistening-roller is arranged at the other end of the device, and either of the rollers 5 and 6 may be used without changing or reversing the device.

15 The arms 4, between which the pressure-roller is mounted, are formed by splitting the sheet metal of which the casing is constructed, and the intermediate portion of the metal is bent inward into the space between the arms 4 to provide a guide portion or 20 flange 11, which extends across the space between the arms and which is arranged at an angle or inclination. This inclined transversely-disposed guide-flange co-operates with a similar guide-flange 12 of a stamp or 25 label holder 13, which is in the form of a pivoted box or receptacle. The box or receptacle consists of a bottom and side and end walls, the guide-flange or portion 12 being carried by and consisting of an extension of the outer or front end wall 14 of the box or 30 holder 13. The guide-flange or portion 12 is spaced from the flange or portion 11 to provide an inclined guide or way for guiding a stamp or label beneath the pressure-roller, 35 which will clamp a stamp or label between it and the envelop or other article and assist in feeding such stamp or label out of the device. The box or holder is provided at its inner end with laterally-extending pivots 15, preferably formed by partially severing portions of the side walls 16 and arranged in openings of the sides 2 of the body or casing of the device. The pivots have their outer portions bent against the outer faces of the sides of the 45 body or casing, whereby the box or holder is prevented from becoming disconnected from the said body or casing through any lateral movement of the sides 2, which are resilient and which are adapted to be compressed and 50 expanded for a purpose hereinafter described. The pivots 15 permit the box or holder to be swung inward and outward to open and close the same, and the said box or holder is retained in its closed position by 55 means of a longitudinal spring 17, which is engaged by a heel 18 of the rear end wall 19 of the box or holder 13. The spring is formed integral with the casing by splitting the same longitudinally at opposite sides of 60 the center, as clearly shown in Fig. 1, and the pressure-severed portion is bowed inward for engagement with the heel, which projects from the upper edge of the rear wall 19 of the box or holder.

65 The box or holder is positively locked in

its closed position by means of a pair of substantially L-shaped catches 20, formed by partially-severed portions of the side walls 16 and bending the partially-severed portions outward, as clearly shown in Figs. 4 and 5. The L-shaped catches engage from the edges of the sides 2 and are provided with projections 21, which engage openings 22 of the sides 2, whereby the box or holder 13 is held against outward movement. The sides 2 are resilient and are adapted to be compressed to carry them out of engagement with the projections of the L-shaped catches, and the sides when released are adapted to spring outward automatically to reengage the said catches. When the sides are compressed inward, the box or holder is adapted to be opened, and the spring 17 and the heel 18 will maintain the box or holder in its closed position until it is positively swung outward. Also the spring will assist the opening of the box or holder and will throw the same outward when the said box or holder is positively opened a short distance by hand.

The stamps are fed out of the box or holder by means of a corrugated feed-roller, which preferably consists of a rubber-covered wooden roller 23 and which is journaled in bearings 24. The inner portion of the feed-roller extends into the casing through an opening 25 thereof to engage the stamps or labels, and portions of the metal cut from the casing to form the opening 25 are bent outward at the ends of the opening to provide projecting ears or arms for supporting the feed-roller. The ears or arms are provided with perforations to receive the journals of the feed-roller and constitute the bearings 24. The opening 25 extends transversely of the casing and is located adjacent to the inner or upper end of the guide or way formed by the flanges 11 and 12.

The stamps or labels are yieldably held in engagement with the corrugated feed-roller by means of a resilient support or clamping-plate 26, constructed of thin spring metal and provided at its rear wall with a flange 27, which is affixed to the rear wall of the box or holder by bending the upper edge of the same inward over the flange 27, as shown. The inner end wall of the box or holder is split at opposite sides of the center into three portions. The central portion forms the heel 18, and the side portions 28 clamp the flange 27. When the box or holder is empty, as shown in Fig. 5, the resilient support or clamping-plate 26 is arranged at an angle to the bottom of the box or holder and extends upward and forwardly, its free front end being in contact with the corrugated feed-roller. The free front portion of the resilient support 2 is forced away from the feed-roller by the stamps, as illustrated in Fig. 2 of the drawings, and as the stamps are used the clamping-plate or support automatically springs 130.

upward and adjusts itself to the stamps left in the device and holds the same against the feed-roller, whereby the device is as effective when there is only a few stamps in it as when 5 the box or holder is full.

The corrugated feed-roller is operated by partially rotating it with the index-finger, and the stamps are pressed forward or outward and are held against backward movement by means of a spring or tongue 29, formed integral with the resilient support or clamping-plate 26 by partially severing the central portions of the same. The spring or tongue 29 extends longitudinally of the resilient support or clamping-plate 26 and is connected at its front end with the same, its rear end being free and bent upward to provide a flange or wall 30. The spring or tongue 29 is arranged at an angle to the resilient support or clamping-plate 26 when it is relieved of pressure, as clearly shown in Fig. 5, and it is adapted to be depressed or bent down into the opening cut into the plate or support 26 in forming the spring or tongue 29.

25 In affixing the stamps or labels the moistening-roller applies the necessary moisture to the surface of the envelop or package, and the corrugated feed-roller is then partially rotated to feed a stamp or label out of the device, and such stamp or label is pressed against the moistened surface by the pressure-roller, which coöperates with the feed-roller in feeding the stamps or labels from the device. Instead, however, of moistening the 35 surface by which the stamp or label is to be affixed the moisture may be directly applied to the gummed surface of the stamp or label when it is impracticable to operate the device as above described.

40 The device is provided at one side with a knife-blade 31, adapted for opening letters and for various other purposes and pivoted at its end 32 to one end of the body or casing by one of the journals 8 of the pressure-roller 45 6. The end 32 of the blade is also provided with an inwardly-extending lug 33, which engages the edge of the side wall 2 when the blade is opened and which thereby limits the opening movement of the same. The blade 50 is supported when closed by means of a keeper 34, consisting of an L-shaped lug or projection extending outward from one of the sides 2 of the body or casing.

Having thus fully described my invention, 55 what I claim as new, and desire to secure by Letters Patent, is—

1. A device of the class described, having a moistening-roller and provided with a projecting foot extending over and spaced from the roller when the device is in use and arranged to support the moistening-roller in a slightly-elevated position when the device is not in use.

2. A device of the class described, having a 65 moistening-roller and provided with a pro-

jecting foot extending over and spaced from the roller when the device is in use and arranged to support the moistening-roller in a slightly-elevated position when the device is not in use, said foot being tapered and constituting a package-opener.

3. A device of the class described, having a moistening-roller and provided with a pair of projecting feet, said feet being tapered and extending on one side of the roller and arranged to support the roller when the device is not in use and adapted also for use as a package-opener.

4. A device of the class described, having means for holding the stamps or labels and provided with a guide or way, a feed-roller arranged to feed the stamps or labels to the guide or way and a pressure-roller located at the outward end of the guide or way to complete the feeding operation and to press the 85 stamps or labels against the surface to which they are to be applied.

5. A device of the class described, provided with means for holding the stamps or labels and having a guide or way, means for feeding the stamps or labels through the guide or way, and a pressure-roller arranged at the outward end of the guide or way to complete the feeding operation.

6. A device of the class described having a stamp or label holder and provided with a guide or way extending from the same, a feed-roller mounted on the device at the inner end of the guide or way and extending into the holder to feed the stamps through 100 the guideway, said feed-roller also projecting exteriorly of the device to enable it to be exteriorly operated, and a pressure-roller arranged at the outer end of the guide or way to complete the feeding of the stamps or labels and to press the same against the surface to which they are to be applied.

7. A device of the class described, having a stamp or label holder and provided with a guide or way extending from the same, and a feed-roller mounted on the device and extending into the holder to feed the stamps or labels through the guide or way, said roller projecting exteriorly of the device to enable it to be rotated by the finger.

8. A device of the class described, having a stamp or label holder, a feed-roller arranged to feed the stamps or labels from the holder, and a resilient clamping-plate located within the holder and receiving the stamps or labels, 120 said clamping-plate being supported at one end and having its other end free and arranged to hold the stamps or labels against the feed-roller.

9. A device of the class described, having a stamp or label holder, a feed-roller, a resilient supporting or clamping plate fixed at its inner end and having its outer end front and a resilient tongue or spring carried by the plate and having its inner end free, said plate 130

and spring being arranged to press the stamps or labels in the direction of the feed-roller.

10. A device of the class described, having a stamp or label holder, a feed-roller and a resilient support or clamping-plate receiving the stamps or labels and holding the same against the feed-roller, said plate having its outer end free and provided with a longitudinally-arranged spring or tongue having its inner end free and provided with a projecting engaging portion.

11. A device of the class described, comprising a casing having a guiding-flange, a box or holder hinged at one end to the casing and provided at its other end with a guiding-flange spaced from the said guiding-flange to form a guideway, and means for feeding the stamps or labels through the guideway.

12. A device of the class described, comprising a casing having resilient sides and a stamp or label holder hinged to the casing and provided with catches engaging the sides of the casing, said sides being compressible to release the stamp or label holder.

13. A device of the class described, comprising a casing having resilient sides, and a stamp or label holder hinged to the casing and provided with L-shaped catches embracing the sides of the casing and provided

with projections for engaging the same to lock the holder in its closed position, said resilient sides being adapted to be compressed to disengage them from the catches.

14. A device of the class described, comprising a casing provided with a spring, a hinged stamp or label holder mounted within the casing and having a projecting portion or heel for engaging the spring, and means for feeding the stamps or labels from the holder, said spring being arranged to move the holder in the direction of the feeding means.

15. A device of the class described, comprising a casing, a moistening-roller located at one end, a pressure-roller arranged at the other end of the casing, a stamp or label holder arranged within the casing at an intermediate point, and a feed-roller also mounted on the casing for feeding the stamps or labels from the holder to the pressure-roller.

In testimony that I claim the foregoing as my own I have hereto affixed my signature in the presence of two witnesses.

GUSTAF F. JOHNSON.
